United States Patent Office.

ARTHUR KIRK, OF ALLEGHENY CITY, PENNSYLVANIA.

Letters Patent No. 78,878, dated June 16, 1868; antedated February 10, 1868.

IMPROVEMENT IN DISTILLING PETROLEUM.

The Schedule referred to in these Letters Patent and making part of the same.

TO ALL WHOM IT MAY CONCERN:

Be it known that I, ARTHUR KIRK, of Allegheny City, in the county of Allegheny, and State of Pennsylvania, have invented a new and useful Improvement in Distillation of Petroleum; and I do hereby declare the following to be a full, clear, and exact description thereof, reference being had to the accompanying drawing, making a part of this specification, in which—

Figure 1 is a front elevation of a nest or battery of stills, with connecting-pipes for passing the oil from still to still, to secure a continuous distillation of the oil, and

Figure 2 is an end view of a still, fitted with my improved devices for regulating the feed, and for ascertaining the amount of residuum remaining at any time in the still during an exhaustive distillation of the oil.

Like letters of reference indicate like parts in each.

The nature of my invention consists, first, in connecting together the consecutive stills in a nest or battery of stills, by pipes, in such a way that as the lighter products of distillation in each still are driven off, the heavier or residual oils will flow along, from still to still, increasing in gravity, and so effect a continuous distillation, with a complete separation of the different products of distillation according to their gravity, such connecting-pipes being so arranged as to perform the function of a trap to prevent the backward flow of the oil; and, second, in combining, with such stills, devices for ascertaining the amount of residual oil remaining at any time in a still in the process of an exhaustive distillation.

To enable others skilled in the art to make and use my invention, I will proceed to describe its construction and manner of use.

The stills *a b c*, in any desirable number, of the usual or any known construction, are built in the furnace-walls *d*, and over suitably-constructed furnaces, which, in the drawing, are closed by the doors *e*. The goose-necks *f* connect with the usual condensing-apparatus for the usual purposes. The stills are connected to each other by pipes *x y z*, each pipe extending from the upper part of one still to the lower part of the next.

The oil is fed into the first still, *a*, either in the usual way, or in the manner yet to be described, till the still is about two-thirds full, more or less. Heat is then applied to the still, and the more volatile ingredients of the oil, as gasoline or benzine, are driven off and condensed in the usual way. A continuous flow into the still, *a*, of crude oil, is kept up, the feeding being somewhat in excess of the evaporation.

As soon as the oil in the first still, *a*, has risen above the upper orifice of the pipe *x*, such oil, thus deprived of its more volatile ingredients, flows through the pipe *x* into the next still, *b*, to which, when about two-thirds full, heat is applied, the next less volatile ingredients are driven off and condensed, and the oil fed in from the still, *a*, rising above the upper open end of the pipe *y*, flows through such pipe *y* into the next still, *c*, and so on into and through as many stills as may be necessary or desirable, in order to secure a complete and exhaustive distillation of the oil, and a complete separation of the different products of distillation, according to their gravity.

In other words, crude oil is fed continuously into the first still *a*, its lightest ingredients driven off, the remaining oil flows continuously into the next still *b*, where the next lightest ingredients are vaporized, and so on from still to still, the products of distillation in each successive still becoming heavier, and the distillation more exhaustive. This process may be continued till only a tarry residuum remains, or it may be arrested at any desirable point.

By introducing the oil thus into the lower parts of the stills, I effect a more complete separation of water, tarry residuum, and other impurities from the oil, they being precipitated and drawn off by suitable stop-cocks, while the oil rises, and is either vaporized or flows on into the next still, as described.

By running the pipes *x y z* from the upper part of one still to, at, or near the bottom of the next, I provide for the onward flow of the oil, but prevent its flowing backwards, that is, so long as the oil in the stills does not rise above the upper ends of the pipes *x y z*. To this end, such pipes act as traps. But if one of the

first stills becomes partially empty, or has less oil than the next still, I quickly supply the deficiency by increasing the feed into the first still, *a*.

Another advantage which I secure is, that the oil being discharged into the stills, at or near the bottom, is heated while rising through the body of the oil, and more readily vaporizes on reaching the surface.

I am also enabled to make a more economical application of heat, since I adapt the fire under each still to the quality of the oil to be driven off, the lighter oils vaporizing at a lower temperature, and *vice versa*. I also effect a complete separation of the several products of distillation, and discharge them from separate condensing-apparatus into separate receiving-tanks.

In connection with the devices described, I use an apparatus for regulating the feed, shown in fig. 2, *a* being the still, and *g* the crude-oil feed-pipe. In this feed-pipe I place a cock or valve, *i*, which is opened or closed by an arm, *i'*. Inside the still is a float, *s*, of any convenient construction, so arranged as to operate a lever, *l*, on the outside of the still. This lever *l* engages the arm *i'* of the valve, and as it rises, closes the valve *i*, and *vice versa*. But the two are so connected that when it is desired to run off all the distillable ingredients of the oil, till only the residuum is left, the lever *l* and arm *i'* may be conveniently disconnected, or so that they will at any fixed point disconnect themselves, when the spring *h*, attached to the arm *i'*, will close the valve *i*, and shut off the supply of oil.

The distillation of the oil in the still, *a*, may then be continued till only the tarry residuum is left, in which case, as the float *s* inside goes down, the lever *l* acts as an index to show the amount of oil or residuum remaining in the still. At the proper time the fire is put out, the residuum removed, the still refilled, and the distillation continued.

I thus construct a nest or battery of stills, by which to distill petroleum, or other substances requiring such treatment, in continuous distillation, with a complete separation of the products of distillation, and also with a self-regulating feed, and index for showing the amount of oil in any one still.

What I claim as my invention, and desire to secure by Letters Patent, is—

1. Effecting a continuous distillation of petroleum, or other distillable substances, by causing it or them to flow through a succession of stills, giving off in each still the more volatile ingredients, the stills being connected by trap-pipes *x y z*, &c., so as to prevent the backward flow of the substance to be distilled, substantially as above set forth.

2. A nest or battery of stills, for purposes of distillation, two or more in number, connected together by pipes, each pipe leading from the upper part of one still to the lower part of another still, substantially in the manner and for the purposes above set forth.

3. In connection with a still, for distilling petroleum, and other distillable substances, the use of a float, *s*, with suitable index-lever *l*, arranged and operated substantially as and for the purposes hereinbefore set forth.

In testimony whereof, I, the said ARTHUR KIRK, have hereunto set my hand.

ARTHUR KIRK.
